UNITED STATES PATENT OFFICE.

LUDWIG PERLHEFTER, OF VIENNA, AUSTRIA-HUNGARY.

AUTOMATIC FARE-COLLECTING APPARATUS FOR STREET-CARS OR OTHER PUBLIC VEHICLES.

SPECIFICATION forming part of Letters Patent No. 699,895, dated May 13, 1902.

Application filed July 18, 1900. Serial No. 24,050. (No model.)

To all whom it may concern:

Be it known that I, LUDWIG PERLHEFTER, a subject of the Emperor of Austria-Hungary, and a resident of Vienna, Austria-Hungary, have invented certain new and useful Improvements in Automatic Fare-Collecting Apparatus for Street-Cars or other Public Vehicles, of which the following is a specification.

- 10 The object of the invention is to dispense with the personnel ordinarily necessitated for sale of tickets, collection of fare, and general oversight and control; and it consists in such an arrangement of turnstiles and coin-controlled apparatus that while a passenger is allowed free admittance to the car he is barred from leaving it until his fare has been personally deposited in a receiver or automatic cashier.
- 15 More particularly, the invention consists in an arrangement of three or more independent turnstiles of any suitable construction in details so disposed that the stile at the boarding-point is revolute only in one determined direction to admit the passenger and that in order to pass out he is obliged to go through a coin-controlled turnstile and finally to leave the car through a third turnstile turning also in one definite direction to permit outgoing, 30 but bar incoming.

Figure 1 represents in top plan view and diagrammatically apparatus constructed, arranged, and combined according to my invention. Fig. 2 is a vertical central section through the central turnstile, enlarged, to show coin-controlled apparatus for locking and releasing said turnstile. Fig. 3 is a fragmental view in horizontal section on lines 3 3 of Fig. 2 on the same scale as the latter figure, the lower coin-hopper being removed; Fig. 4, a vertical section, partly broken away, on line 4 4 of Fig. 3; and Fig. 5, a detail.

Referring to said drawings, it will be seen that to provide for the exigencies of traveling in both directions where entrance and exit must be made at and from a given side of the car, for the purposes of this case the left-hand side, each platform is provided with two turnstiles, one for entrance and one for exit, the corresponding stiles for each platform being diagonally opposite each other.

Assuming that the direction in which the car is traveling is represented by the heavy arrow 1, the passenger entering and departing follows the path indicated by the heavy arrows 2—that is, he enters at the turnstile A, passes through the usual sliding door into a compartment H, representing for the time the rear half of the closed car and divided off from the front compartment H' by partitions h and central turnstile C, carrying an automatic cashier g, which releases the stile upon the deposit of a suitable coin therein. All of the turnstiles are composed of crossed arms a, rotating about a central vertical standard b, and all of the platform-turnstiles have ratchets c c' and pawls d d' to control the direction in which they move, the only difference in this respect being that whereas the ratchets c and pawls d of the entrance-turnstiles are so set as to permit inward revolution only the ratchets c' and pawls d' of the exit-stiles are so disposed as to bar entrance, but permit exit. Guards e are arranged in connection with the platform-stiles to prevent their being flanked. The turnstile C differs from the platform-stiles only in omitting the pawl and ratchet and in having a coin-controlled step-by-step movement which permits the passage of but one person at a time for each coin deposited. This automatic control apparatus or cashier forms in itself no part of the present invention; but for a full understanding of the mode of operation of my improved apparatus I will proceed to describe coin-controlled devices adapted to coact therewith in contributing to the result sought.

The head C' of the turnstile C is rotatably mounted upon the hollow standard b by means of a rabbeted bearing-joint b' and screws f, taking into a circumferential groove f' in the standard. To the upper part of the standard opposite this joint is rigidly secured a bridge-plate K, from which rises a spindle K', supporting at its upper end a coin-hopper K² immediately beneath the coin-slot k centrally through the cap of the turnstile. Upon this spindle beneath the coin-hopper is mounted a hub L, having four arms l, to which are rigidly secured the inner ends of the four turnstile-levers a, which sustain the hub at

a definite height on the spindle by being passed through close-fitting apertures a' in the sides of the turnstile-head. From each of the hub-arms depends a finger $l' l^2$, &c., reaching into close proximity with the bridge-plate, and all four being concentric with the spindle, so as to follow exactly the same path as the hub turns therearound. Substantially radial to the spindle and moving in a keeper m , secured to the bridge-plate, is a bar M , normally pushed inward by spring m' to project its beveled inner end m^2 into the path of the depending fingers $l' l^2$, &c., hereinafter termed the "stop-fingers," so that it may be struck thereby and pushed back like a spring-bolt door-latch. The heel end of this bar is bent at right angles to form a jaw m^3 for a purpose that will immediately appear. In rear of the bar M is a second bar N or stop-bar, sliding in a guide in the same keeper, parallel with and at its inner end held up against the inner end of said bar M or latch-bar by an abutment n , which resists the lateral thrust of the stop-fingers. This stop-bar N , like the latch-bar, is normally pressed inward by a spring n' , which brings its inner flat end n^2 nearly or quite flush with the extreme inner end of the beveled latch-bar. At its outer end the stop-bar is also bent at right angles to form a jaw n^3 parallel with jaw m^3 , but just sufficiently removed therefrom to admit the appropriate coin for the fare flatwise between the two jaws. The chute k' of the coin-hopper K^2 terminates just above the path of movement of the hub-arms l , so as not to interfere with their action, and immediately beneath that path is a second hopper O , receiving therefrom, and the chute o of which is directed to the opening between the jaws m^3 to deliver the coin flatwise therebetween. Now supposing that it is attempted to revolve the turnstile forward when there is no coin between the jaws the stop-finger l' , which has been until this moment resting against the base of the bevel m^2 , will be forced thereagainst and push the latch-bar back against the force of its spring, as indicated in Fig. 5; but there being at the time no connection between the latch-bar and the stop-bar the latter will not be operated, but will still block the path of the finger, while jaw m^3 will approach jaw n^3 . As soon, however, as the attempt to turn the stile is relinquished, the latch-bar will be forced forward by its spring and the bevel m^2 will force the finger l' back, and with it the entire revolvable part of the stile, until the space between the coin-jaws $m^3 n^3$ is again normal. If, on the other hand, it is attempted to revolve the turnstile backward, the stop-finger l^4 that has last passed will come against the rear side of the stop-bar and be blocked thereby; but if a suitable coin has been deposited it will fall through the two hoppers and their chutes until it finally rests flatwise and snugly upon the bridge-plate and between the coin-jaws. Then if the turnstile is pushed forward, forc-

ing the latch-bar outward, the jaw m^3 cannot approach jaw n^3 , owing to the presence of the coin between them. Therefore stop-bar N is forced to accompany the latch-bar in its outward journey until finally stop-finger l' rides off the crest of the bevel m^2 and upon the flat terminal face n^2 of the stop-bar, holding the latter momentarily back while the latch-bar, released, flies forward and closes behind said finger. This forward movement opens the coin-jaws, and the coin, which has been brought by said outward movement over an opening p through the bridge-plate, drops therethrough and into a receptacle P in the hollow standard, whence it can be removed when the collector comes around by means of drawer P' or other suitable agency.

After entering compartment H the passenger may remain there until ready to get off the car, provided there is no exit-turnstile on the platform behind him or that such exit-turnstile has been locked for the trip, as it will be in practice, or he may enter compartment H' by payment of his fare. As this is the first step toward getting off, it will be assumed that he remains in compartment H to his journey's end, then deposits a suitable coin for payment of his fare in the automatic cashier, thereby releasing turnstile C and allowing it to swing one step, or, say, ninety degrees, and permit him to pass, traverse compartment H' , and depart through turnstile B , which opens outwardly on the same side of the car that he entered; but if the car is going in the direction indicated by the dotted arrow 1^a the passenger will enter through turnstile A' and follow the route indicated by dotted arrows 2^a , through compartment H' , coin-controlled turnstile C , compartment H , to turnstile B' , where he quits the car.

Having thus described my invention, what I claim, and desire to secure by Letters Patent, is—

1. The combination in a vehicle of means for permitting entrance but barring exit, means for permitting exit but barring entrance, a passage between the two, and coin-controlled step-by-step mechanism blocking said passage except upon the deposit of a suitable coin.

2. The combination, in a vehicle, of a turnstile permitting entrance and barring exit, a turnstile permitting exit and barring entrance, and an intermediate coin-controlled turnstile barring passage between the other two except when released upon the deposit of a suitable coin.

3. The combination, in a vehicle having end platforms, of two turnstiles on each platform, one barring exit and permitting entrance, and the other barring entrance and permitting exit, the corresponding turnstiles for each platform being arranged diagonally opposite each other, and an intermediate coin-controlled turnstile placed between the platforms and blocking the only passage from the entrance-turnstiles to their relative exit-stiles.

4. The combination of the entrance-turn-

stile at one end of the car or vehicle, arranged to bar exit, the exit-turnstile at the other end of the car or vehicle, arranged to bar entrance, the partition dividing the car into front 5 and rear compartments, and the coin - controlled turnstile blocking the passage between these compartments.

In testimony whereof I affix my signature in presence of two witnesses.

LUDWIG PERLHEFTER.
